UNITED STATES PATENT OFFICE.

THOMAS J. CHRISTY, OF ST. LOUIS, MISSOURI, ASSIGNOR OF ONE-HALF TO
JOHN C. KLEIBER AND JOHN M. LOEBLEIN, OF SAME PLACE.

DESIGN FOR A GENERATOR FOR VAPOR-LAMPS.

SPECIFICATION forming part of Design No. 30,726, dated May 9, 1899.

Application filed March 30, 1899. Serial No. 711,171. Term of patent 3½ years.

To all whom it may concern:

Be it known that I, THOMAS J. CHRISTY, a citizen of the United States, residing in the city of St. Louis, State of Missouri, have invented and produced a new and original Design for a Generator for Vapor-Lamps, of which the following is a specification.

Figure I is a side elevation of a generator for a vapor-lamp embodying my new design as seen looking in the direction indicated by the arrow I in Fig. II. Fig. II is a top plan view seen looking in the direction indicated by the arrow II in Fig. I.

As seen in the drawings, the leading or essential feature of my new design for a generator for vapor-lamps is the spiral coiled

central portion 1, the arm 2, extending from the upper end of the coiled central portion, and the arm 3, extending from the lower end of the coiled central portion. The arm 2 is ²⁵ somewhat longer than the arm 3 and terminates with an enlargement which is screw-threaded, and the arm 3 terminates with a slight enlargement.

I claim—

The design for a generator for vapor-lamps, substantially as herein shown and described.

THOMAS J. CHRISTY.
